UNITED STATES PATENT OFFICE.

WILLIAM R. RAY, OF SAN FRANCISCO, CALIFORNIA.

OIL-BURNER.

1,253,422.

Specification of Letters Patent. Patented Jan. 15, 1918.

Application filed May 8, 1916. Serial No. 96,107.

To all whom it may concern:

Be it known that I, WILLIAM R. RAY, a citizen of the United States, residing at the city and county of San Francisco and State of California, have invented new and useful Improvements in Oil-Burners, of which the following is a specification.

This invention relates to oil burners and pertains especially to rotary burners of the type shown and described in my pending application Serial Number 874,754, filed November 30, 1914, entitled "Oil burners."

One of the objects of the present invention is to provide a hollow motor shaft having a stationary fuel oil feeding pipe passing therethrough to permit delivery of the oil to the rotary atomizer through the shaft, thus permitting partial cooling of the motor, and similarly a pre-heating of the oil before delivery to the atomizer. Another object of the invention is to provide means for centering and adjusting the position of the oil delivering pipe with relation to the interior wall of the hollow motor shaft. A further object is to inclose the motor proper with an open-ended casing and to connect one end of said casing with the suction side of the fan; in this manner causing a constant in-rush of air around the motor which cools the same and similarly raises the temperature of the air.

Further objects will hereinafter appear.

The invention consists of the parts and the construction and combination of parts as hereinafter more fully described and claimed, in which—

Figure 1 is a side elevation of the oil burner partly in section.

Fig. 2 is a cross section of line 2—2, Fig. 1.

Fig. 3 is a longitudinal section through the motor shaft, showing the position of the stationary oil delivering tube and the means whereby it is adjusted.

Referring to the drawings in detail, A indicates a motor; 2 the motor shaft which in this instance is hollow, and 3 a centrifugal atomizer secured on the outer end of the hollow shaft. Oil is delivered to the atomizer through a stationary pipe 3' passing through the shaft and air to assist combustion and also atomization of the oil discharged by the atomizer is delivered from a high pressure fan generally indicated at B also secured upon the shaft 2 and driven in unison with same. Surrounding the outer bearing 4 of the motor and secured to the

bracket 5 which supports said bearing is a cap-like member 6. This member is provided with a plurality of arms 7 and an extension 8 which is adapted to receive a valve 9 of any suitable construction. The stationary pipe 3' is screwed into the extension 8 as indicated at 10, and oil delivered by the valve 9 passes down through a passage 11 directly into pipe 3'. The oil is then permitted to discharge into the inner end of the atomizing cup through a goose-neck extension 12 which is adapted to telescope with relation to the pipe 3'. Formed on the cap-like member 6 is the sleeve-like projection 13. This is positioned interior of the arms 7 and is larger in diameter than the pipe 3' which passes therethrough. Passing through the sleeve 13 is a plurality of adjusting screws 14 preferably four in number. These screws are adapted to engage the pipe 3' and spring it in one direction or another, in this manner preventing rubbing of the pipe against the interior wall of the shaft and making it possible to adjust the position of the pipe 3' to assume an exact central position. The extension 8 is preferably provided with a screw plug 16 at its outer end which may be removed as occasion demands, to permit insertion of a cleaning rod or like means not here shown. A rod inserted at this point may be forced directly through the pipe 3' and will in this manner remove any carbonized oil or other substance which might have a tendency to choke the feed pipe. The said pipe supported and connected as here shown is simple and substantial in construction, is leak-proof and may be applied to practically any form of centrifugal atomizing burner of a type here shown. In the operation of electric motors of the type shown, it is well known that the high speed of the armature produces considerable heating action. This heat is employed to advantage in the present instance as it is transmitted through the shaft 2 to the oil delivering pipe 3', in this manner raising the temperature of the oil to such an extent that it is more easily handled by the centrifugal atomizer and conversely an advantageous reduction of motor temperature is obtained. For the purpose of further decreasing the temperature of the motor an open-ended casing, generally indicated at 17 has been provided. One end of this casing is connected with the suction side or intake opening 18 of the fan. A constant in-rush of

air around the motor is thus insured which not only reduces its temperature, but it also causes a considerable increase in the temperature of the air before it passes through 5 the fan and reaches the fire zone.

The materials and finish of the several parts may otherwise be such as the judgment and experience of the manufacturer may dictate.

10 I wish it understood that various changes in form, proportions and minor details of construction may be resorted to within the scope of the appended claims, and that I do not wish to limit myself to the specific 15 design and construction here shown.

The furnace plate together with the hinge mounting of the fan casing and the oil connections formed through the hinges, although shown, does not form a part of the 20 present application as it is more thoroughly illustrated and claimed in my co-pending application, Serial No. 96,108, filed May 8, 1916, entitled Oil burner.

Having thus described my invention, 25 what I claim and desire to secure by Letters Patent is:

1. In an oil burner, the combination with an electric motor having a hollow shaft, of an atomizing head secured on one end of 30 the shaft, a stationary pipe extending through the hollow shaft to deliver oil to the atomizer and adapted to cool the motor and heat the oil, and means for adjusting the oil delivering pipe with relation to the 35 interior wall of the hollow shaft.

2. The combination with a motor, a hollow motor shaft, and an atomizing cup secured on the shaft, of a stationary pipe extending through the shaft and having one 40 end extending into the atomizer, means for delivering oil to the stationary pipe, and adjustable means engageable with the stationary pipe to spring or bend it with relation to the interior of the hollow shaft.

45 3. The combination with a motor, a hollow shaft, and an atomizing cup secured on the shaft, of a stationary pipe extending through the shaft and having one end extending into the atomizer, a stationary support for the opposite end of the pipe, having a passage formed therein communicating with the pipe, means for delivering oil to said passage and a plurality of set-screws in the support engageable with the pipe to 55 adjust its position with relation to the interior of the hollow shaft.

4. In an oil burner, the combination with a hollow shaft, of means for revolving the shaft, a centrifugal atomizer on one end 60 of the shaft, a stationary pipe extending through the shaft and opening into the

atomizer, a stationary member supporting the opposite end of the pipe, said member having a passage formed therein communicating with the pipe, means for delivering oil to the passage, means for regulating the flow of oil through the passage, and means engageable with the stationary pipe adapted to bend or spring it with relation to the interior of the hollow motor shaft. 70

5. In an oil burner, the combination with a hollow shaft, of means for revolving the shaft, a centrifugal atomizer on one end of the shaft, a stationary pipe extending through the shaft and opening into the atomizer, a stationary member supporting the opposite end of the pipe, said member having a passage formed therein communicating with the pipe, means for delivering oil to the passage, means for regulating the flow of oil through the passage, and means carried by the support for centering the pipe with relation to the interior of the hollow shaft and the atomizer. 80

6. The combination with a motor, a hollow shaft, a fan and an atomizing cup secured on the shaft, of a stationary pipe extending through the shaft and having one end extending into the atomizer, an open ended casing inclosing the motor, said casing having one end opening to the atmosphere and the opposite end connected with the suction side of the fan and means for delivering oil to the opposite end of the stationary pipe. 90

7. In an oil burner, an electric motor having a hollow shaft, an atomizing cup secured on one end of said shaft, a stationary pipe passing through the hollow shaft and extending into the atomizing cup, and means for passing oil through said pipe to the atomizing cup to permit the oil during its passage to become heated by heat radiated from the motor and simultaneously to partially remove said heat to cool the motor. 100

8. In an oil burner, an electric motor having a hollow shaft, an atomizing cup secured on one end of the hollow shaft, and means for passing oil through the hollow shaft to the atomizing cup to permit the oil during its passage through the shaft to become heated by heat conducted from the motor and simultaneously to partially remove said heat to cool the motor. 110

In testimony whereof I have hereunto set my hand in the presence of two subscribing witnesses.

WILLIAM R. RAY.
